UNITED STATES PATENT OFFICE.

HEREWARD M. MACK AND WALLACE P. ANDRICK, OF NEW YORK, N. Y., ASSIGNEES TO
GENERAL ACOUSTIC COMPANY, A CORPORATION OF NEW YORK.

JUNCTION-BOARD.

1,122,290.

Specification of Letters Patent. Patented Dec. 29, 1914.

Application filed January 21, 1913. Serial No. 743,248.

To all whom it may concern:

Be it known that we, HEREWARD M. MACK and WALLACE P. ANDRICK, citizens of the United States, residing at the city of New York, in the borough of Queens and State of New York, have invented certain new and useful Improvements in Junction-Boards, of which the following is a full, clear, and exact description.

10 This invention relates to junction-boards for electric wires. The function of such devices is to enable of the ready connection and disconnection of the corresponding wires in cables at their abutting ends.

15 The object of the present invention is to provide a junction-board which is adapted to be attached to a wall or a like supporting structure and which shall be cheaper to construct than the devices heretofore used

20 and by means of which the connections and disconnections can be more rapidly and effectively made and in which the abutting ends of the cables are disposed in such a manner as to avoid confusion, misidentification and cross or short-circuiting of the wires.

A further object is to provide a construction of junction-board which can be built up in sections to any desired size or capacity, such a board having the advantage that it requires no more screws or other attaching devices to support it in place than does a smaller board.

The invention consists of the structural details which will now be particularly pointed out and claimed.

In the accompanying drawing, Figure 1 is a longitudinal section of our improved junction-board with its protecting housing, the section being taken on the line 1—1 of Fig. 2; Fig. 2 is a plan of the junction-board with a part broken away and with the housing in horizontal section, and Fig. 3 is a transverse section of the junction-board and its housing, together with the cable ends and conductors therein, taken on line 3—3 of Fig. 2.

The junction-board proper consists of a base or board 1 which, depending upon its required capacity, may comprise one or more sections placed together, end to end, as indicated at the line of joinder 2, any suitable mechanical device being used to secure the sections together. The device we have shown consists of two pins 3—3, which

are anchored in the end of one section and pass into corresponding holes or sockets 4 in the other section. The pins fit friction-tight in the sockets so as to form a rigid joint between the parts. Obviously, any number of such sections may be connected together in the same manner to form one large board of any required capacity. The board of whatever size is provided on its under side at each end with metallic strips 5 secured thereto by screws 6, the strips having downwardly bent ends 7 and outwardly turned feet 8, which are adapted to rest upon the wall or other support to which the board is to be secured, for which purpose securing screws will pass through the perforations 9 in the feet portions 8. Thus, the board is held in spaced relation to its support, the purpose of which is to provide room for the two cable ends entering from the respective ends of the board, the wires of which are to be interconnected by means of the devices on the board.

The board or base 1 will generally be of elongated rectangular shape, and be made of wood, fiber, hard rubber, or other suitable insulating material. Along its two longitudinal edges are formed the notches 10, arranged successively at short and equal distances apart and throughout practically the entire length of the board. These notches are of rectangular formation, extending through the board from top to bottom, and those on one edge are arranged directly opposite or in line, respectively, with those on the opposite edge. On the under face of the board, these notches are connected together in pairs by transverse grooves 11. In each of these grooves is seated the middle portion of a U-shaped metallic connector 12 the arms of which pass through perforations in the base 1 and project beyond the upper or outer face of the base a short distance where they are turned inward toward each other to form a kind of hook 13. These connectors are preferably made of stiff wire of such size as to lie below the surface of the base when they are fully pressed into the groove 11, while the perforations in the base through which the arms extend are of such size as to require the arms to be forced through them, so that when once inserted in the base the connectors are retained therein without any extraneous fastening means. These connectors are located regularly along

the middle of the board and since they occupy the grooves connecting the edge notches together, there will be one connector in the same plane with each pair of the notches 10.

To establish the connections between the wires of the two cable ends, the latter are passed longitudinally under the respective ends of the board and parallel to each other. 10 When thus disposed the wires of each cable are "fanned" out and those wires in the two cables which are to be connected together are carried upward or outward through two of the notches 10 on opposite edges of the 15 board which correspond or are in line with each other, as indicated, for instance, by the two wires 14 and 15 in Fig. 3. Then they are bent inward toward the hooks 13, and cut off at the proper length to engage with 20 said hooks; then the ends of the wire are stripped and bent around said hooks respectively, after which a drop of solder is applied to each hook to secure the wire thereto. Thus the electrical connection is 25 established between the two wires of the two cable ends through the intermediacy of the U-shaped connector. All of the other wires in the two cable ends are correspondingly connected together, one of the U-shaped connectors being appropriated for each pair of 30 wires. To disconnect any of the wires, it is only necessary to apply a hot iron to the hooks for an instant to melt the solder.

In most forms of junction-boards heretofore in use, the wires are held by some form of binding screw which, on account of the metallic parts necessarily associated with such devices, is more expensive than the structure we have provided. Furthermore, 40 binding screws occupy more space than the hooked connectors herein provided and not only can fewer of them be placed in a given space, but the metallic parts are liable to be mounted in such close proximity to each 45 other on account of their size as to render short and cross circuits likely. In no other junction-board known to us are the cable ends disposed behind the board itself; they are usually secured to the wall adjacent the 50 board or to the face of the board itself by means of staples. Such disposition of the wires necessarily gives rise to confusion and requires more time and care in making the connections. In our construction, the two 55 wires which are to be connected are at once separated from the others as soon as they have been deposited in the edge notches and there is no danger of confusing them with others when they are so disposed, since all 60 of the other wires are either already connected to the hooks or remain behind the board. Inasmuch as that portion of the connectors which lies in the groove 11 on the under face of the base 1 is below the surface of the base, it cannot come in contact

with any of the wires in the cable ends and even if this did occur, it would ordinarily do no harm, since the wires are insulated. Cross and short-circuits are therefore not to be expected in this device, either above 70 or below the face of the board. When the connections are all made, the board is covered by the housing 16, which is an ordinary box having one side open with the ends provided with passages 17 to accommodate the 75 cables. This housing is held in position by screws 18 which pass down through the ends of the base 1 and into the metallic plates 5 secured thereto.

What we claim as new and desire to secure by Letters Patent of the United States, 80 is—

1. The combination with a pair of cable ends containing electrical wires to be connected together, of a junction board for 85 electrically connecting said wires, said board comprising a plate of insulating material adapted to be secured to a wall or like supporting structure and supporting means therefor spacing said plate from said supporting structure, the pair of cable ends being positioned in the space between said plate and its supporting structure; alining notches in the opposite side edges of the board; integral U-shaped connectors having 90 their middle portions located adjacent the rear face of the board and their arms passing through and projecting beyond the front face of the board, the arms of a pair of connectors and a pair of alining notches being 95 arranged in alinement with each other, whereby the wires of the respective cables may be passed up through said notches and attached to the connectors on the front face of the board. 100

2. A junction board for connecting the ends of the electrical wires in a pair of cables comprising a plate of insulating material, supporting members for said plate spacing said plate from its supporting 110 structure, a plurality of alining transverse notches in the opposite side edges of said board; integral U-shaped connectors having their middle portions resting against the rear face of the plate and their arms passing through perforations in the plate and projecting beyond the front face of the plate; said connectors fitting snugly in said 115 perforations to maintain them in fixed relation to the base, the arms of said connectors being arranged in line with the corresponding notches in the edges of the plate. 120

3. The combination with a pair of cable ends containing electrical wires to be connected together, of a junction board for electrically connecting said wires, said board comprising a plate of insulating material adapted to be secured to a wall or like supporting structure and supporting means therefor spacing said plate from its support- 125 130

ing structure, the pair of cable ends being positioned in the space between said plate and its supporting structure; alining notches in the opposite side edges of the board; integral U-shaped connectors having their middle portions resting against the rear face of the plate and their arms passing through the board and projecting beyond the front face thereof, said board having openings therein through which said arms pass and said connectors being maintained in position on said board by the frictional engagement of said arms with the walls of said openings, the arms of a pair

of connectors and a pair of alining notches 15 being arranged in alinement with each other, whereby the wires of the respective cable ends may be passed up through said notches and attached to the connectors on the front face of the board. 23

In witness whereof, we subscribe our signatures, in the presence of two witnesses.
